GUSTAV HONEGGER, OF ZOLLIKON, NEAR ZURICH, SWITZERLAND.

PACKING FOR PISTONS.

1,284,341.

Specification of Letters Patent. Patented Nov. 12, 1918.

Application filed May 25, 1917. Serial No. 170,924.

To all whom it may concern:

Be it known that I, GUSTAV HONEGGER, a citizen of the Republic of Switzerland, residing at Zollikon, near Zurich, Rütistrasse 5 325, Switzerland, have invented certain new and useful Improvements in Packings for Pistons; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 The present invention relates to packings for pistons and has for its object to provide automatic devices for readjusting such packing in such a manner that its tightness depends on and is controlled by 20 the working pressure.

Packings of this kind have not so far been proposed. Disk pistons have been provided either with spring rings when they may be employed for low pressure work 25 only, or else with leather collars only suitable for work with cold, chemically pure liquids. Again, with plunger pistons, inner or outer packings may be used but these have to be readjusted by hand from within 30 or from without.

According to this invention, automatic readjustment of a piston-packing is caused by the working pressure being admitted into the interior of a diaphragm ring which is 35 arranged in the disk piston and which by expanding under the action of such pressure forces the packing material outward and against the wall of the pump cylinder. It will be seen that in this case the tightness 40 of the packing or the force acting on the packing material is dependent on and automatically controlled by the working pressure.

The accompanying drawings represent 45 different designs constructed according to this invention.

Figure 1 shows a disk piston having a single diaphragm ring and a valve governed by the working pressure and serving to connect the inner space of the diaphragm ring 50 with the pressure side of the pump.

Fig. 2 shows a disk piston having two diaphragm rings either of which constantly communicates with the adjacent piston side.

55 Referring now to Fig. 1, the construction there shown is as follows.

1 is a piston rod upon which are secured the disk piston 2 and the junk ring 3. Inclosing the piston body 2 is a diaphragm ring 4 within which an expanding ring 5 60 with opening 6 is arranged. The diaphragm ring 4 is pressed against the piston body 2 by the junk ring 3 and is held tight by means of packings 7. Drilled through the piston body 2 is a bore 8 in which a 65 valve 9 is movable between two valve seats 10 having openings 11. Inclosing the diaphragm ring 4 is a split spring ring 12 carrying the packing material 13. A hole 14 in the piston body 2 connects the opening 6 70 to the bore 8, while bores 15 are held closed by means of spring valves 16. In the design shown in Fig. 1 the action of the parts is the following:

At the beginning of each piston stroke, 75 the working pressure is admitted to the bore 8 and forces the valve 9 backward against its left-hand seat 10, so that the hole 14 is cleared and the interior of the diaphragm ring 4, while cut off from the suction side, is 80 put under working pressure. This causes the diaphragm and the split spring ring 12 to expand in a radial sense, so that the packing material is forced out against the cylinder wall and the piston is automatically held 85 tight.

Expansion of the diaphragm ring continues until the end of the stroke, when the valve 9 is forced back against its right-hand seat and the working pressure is admitted to the diaphragm from the opposite side of the piston. In order to avoid back-pressure acting on the outside of the diaphragm ring and thereby counter-acting the expanding force of the compressed liquid 90 95 in the interior of the diaphragm ring, the outer surface of the latter is kept in communication with the suction side by means of the split in ring 12, bores 15 and spring valves 16.

100 Referring now to Fig. 2, 1 is the piston rod carrying the disk piston 2 and junk rings 3. Upon the hub of the piston body are arranged two diaphragm rings 4 each inclosing one expanding ring 5 with opening 6. These diaphragm rings 4 are pressed against the piston body 2 by the junk rings 3 and are held tight by means of packings 7. From either side of the piston body bores 8 are drilled into it and these communicate through holes 14 with the openings 6. Inclosing each diaphragm ring 4

is a split spring ring 12 and these rings carry the packing material 13. Bores such as 15, 17 and 18 are provided to connect the outer surface of the diaphragm ring with the suction pipe (not shown) of the pump.

In the design shown in Fig. 2, the action of the parts is as follows.

At the beginning of each piston stroke, the bores 8, 14 and 6 admit working pressure to the interior of that diaphragm ring which is on the pressure-side of the piston. This causes the diaphragm ring and the split ring 12 to expand in a radial sense, so that the packing material is forced out against the cylinder wall and the piston is automatically held tight.

While the interior of the diaphragm ring is kept under working pressure, its outer circumference is automatically relieved by being connected with the suction side through bores 15, 17 and 18.

When one of the diaphragms is under working pressure, the other one, adjacent to the suction side, remains relieved.

When the motion of the piston is reversed, obviously the diaphragm which has been under pressure till then will be relieved and vice versa.

If desired, the pressure admitted into the interior of the diaphragm can be made independent of the working pressure by being derived from outside through a bore in the piston rod.

What I claim is:

1. A piston of the character described, comprising a piston body, a resilient diaphragm ring held fast at the open inner circumference by said piston body but freely movable at the outer circumference and at the lateral surfaces, said surfaces being so formed that the outer circumference can execute a radial resilient movement, packing material arranged around the outer circumference of the resilient diaphragm ring, and means for supplying a pressure medium into the interior of the said diaphragm ring.

2. A piston of the character described, comprising a piston body, a resilient diaphragm ring held fast at the open inner circumference by said piston body but freely movable at the outer circumference and at the lateral surfaces, which latter converge from the outer diameter of the diaphragm ring toward its inner diameter so that its outer circumference can execute a radial resilient movement, packing material arranged around the outer circumference of the resilient diaphragm ring, and means for supplying a pressure medium into the interior of the said diaphragm ring.

3. A piston of the character described, comprising a piston body, a resilient diaphragm ring held fast at the open inner circumference by said piston body but freely movable at the outer circumference and at

the lateral surfaces, said surfaces being so formed that the outer circumference can execute a radial resilient movement, packing material arranged around the outer circumference of the diaphragm ring, means for supplying a pressure medium into the interior of the said diaphragm ring, packing material arranged around the outer circumference of the resilient diaphragm ring, and means for relieving the space inclosing the outer circumference of the diaphragm ring, whereby the outward pressure of the diaphragm ring is not counteracted.

4. A piston of the character described, comprising a piston body, a resilient diaphragm ring disposed in an annular recess of said body and held fast on said body by turned-out edges which form the open inner circumference, said ring being freely movable at the outer circumference and at the lateral surfaces, which latter are formed so that the outer circumference can execute a radial resilient movement, said piston body being provided with holes through which the working pressure is admitted into the interior of the diaphragm ring, and packing material arranged around the outer circumference of said diaphragm ring.

5. A piston of the character described, comprising a piston body, a resilient ring arranged in an annular recess provided in said piston body, a second resilient diaphragm ring arranged in a second annular recess provided in said piston body, each of said diaphragm rings being held fast at the open inner circumference by said piston body but being freely movable at the outer circumference and at the lateral surfaces, which latter are so formed that the outer circumference can execute a radial resilient movement, packing material arranged around the outer circumference of each resilient diaphragm ring, means for supplying a pressure medium into the interior of the said diaphragm rings, and means for relieving the spaces inclosing the outer circumference of the diaphragm rings of any overpressure occurring in said spaces, whereby the outward pressure of the diaphragm rings is not counteracted.

6. A piston of the character described, comprising a rod, a disk piston carried by said rod, a junk-ring on either side of the disk piston and carried by said rod, the disk piston and the junk-rings forming two annular spaces, a resilient ring arranged in each of said spaces, said rings being held fast by the piston disk and by the junk-rings on turned-out edges which form the open inner circumference, said ring being freely movable at the outer circumference and at the lateral surfaces which are so formed that the outer circumference can execute a radial resilient movement, packing material ar-

ranged around the outer circumference of the resilient diaphragm rings, and means for supplying a pressure medium into the interior of the said diaphragm rings, said disk, 5 piston and rod being provided with holes communicating with the spaces inclosing the outer circumference of the diaphragm rings, said spaces being relieved by means of said holes, of any overpressure occurring therein whereby the outward pressure of the dia- 10 phragm rings is not counteracted.

In testimony that I claim the foregoing as my invention, I have signed my name.

GUSTAV HONEGGER.
